UNITED STATES PATENT OFFICE

LOTHAR R. ZIFFERER, OF COLUMBIA, PENNSYLVANIA

FLOOR AND CEILING PLATE

Application filed April 2, 1928. Serial No. 266,845.

This invention relates to a floor and ceiling plate adapted to be secured upon a pipe, post, rod, column, or the like, adjacent the ceiling, wall or floor. The principal object of this invention is to provide a simple yet practical floor and ceiling plate which may readily be applied to the pipe or other device and capable of being readily removed therefrom should occasion arise for removing it. Another object is to provide a floor and ceiling plate having an annular body portion with a separate spring plate or plates secured upon the rear side of the body portion and formed with flexible or resilient tongues adapted to frictionally engage with a pipe or other device, and thereby hold the floor and ceiling plate in adjusted position.

The invention consists in the several novel features of construction, arrangement and combinations of parts hereinafter fully set forth and claimed.

The invention is clearly illustrated in the drawing accompanying this specification in which—

25 Figure 1 is a plan of a floor and ceiling plate embodying a simple form of the present invention;

Fig. 2 is a plan looking at the inner side of the floor and ceiling plate;

30 Fig. 3 is a detail vertical cross section taken on the line 3—3 of Fig. 1, and showing the floor and ceiling plate applied to a pipe;

Fig. 4 is a detail vertical cross section taken on the line 4—4 of Fig. 1;

35 Fig. 5 is a detail vertical cross section taken on the line 5—5 of Fig. 2; and

Fig. 6 is a detail vertical cross section taken on the line 6—6 of Fig. 2.

Referring to said drawing, which illustrates a simple embodiment of the present invention, the reference character 7 designates a fragment of a pipe, and 8 designates a fragment of a ceiling through which said device extends. The floor and ceiling plate forming the subject matter of this specification is seen at 9, and, as shown in Fig. 3, surrounds the pipe and is held thereby against the lower face of the ceiling 8.

In the simple form of the invention illustrated, the floor and ceiling plate comprises

an annular body portion 10, preferably formed of two substantially similar halves 10^a and 10^b pivotally connected together, as, for instance, by means of a rivet 11. By forming the plate of two parts pivotally secured together, the plate may be readily applied to or removed from the pipe after the pipe has been installed in the building. The body portion is preferably formed with a flat part 12 having a marginal rim 13 along its outer edge, and the inner portion of said flat part is struck up to provide an annular bead 14, thus giving an ornamental and finished appearance to the external side of the plate.

Secured on the inner side of the body portion are two arcuate pipe or rod gripping members 15, each of which is preferably formed of a spring plate comprising a flat portion 16 lying upon the inner face of the flat part 12 of the body portion and having downwardly or backwardly bent fingers or tongues 17, the free ends of which are disposed along a circular line and adapted to frictionally engage with the pipe upon which the plate is placed. Each spring plate 15 is formed with down turned tongues 18 which lie along the inner face of the beaded part 14 of the body portion 10, and said body portion is formed with struck up lugs 19 at its outer margin and with lugs 20 at its inner margin, as indicated in the drawing. The lugs so formed may overlie the edge portions of the spring plates and be clamped down thereon, so as to securely fasten the spring plates to the body portion.

Means are provided for locking the two halves of the ceiling plate together upon the pipe, upon which the ceiling plate is secured, and in the form of the invention shown, said locking means comprises a locking tongue 21 formed upon one of the spring plates 15 and containing a slot or opening 22 in which is received a locking lug 23 struck up from an adjacent edge of the half of the body portion on which the other spring plate is secured. As a preference, the locking tongue 21 is formed with a reverse curve, as is shown in Fig. 4, in order to permit the lug 23 to pass underneath the end portion of the locking tongue when the

two halves are being brought together in the locked position.

To unlock the two halves of the ceiling plate, it is necessary to lift the locking tongue 21 above the upper edge of the locking lug 23, and in order to permit the locking tongue to be lifted, an aperture 24 is provided in the body portion 10 immediately below the end portion of the locking tongue, through which 10 a wire 24^a or other instrument of small diameter may be inserted and pressed against the tongue. In order to positively prevent any lateral displacement between the meeting ends of the two halves of the flange, each half is 15 provided with a lug 25 which engages with the inner face of the other half, as seen in Figs. 2 and 5. The two lugs being disposed in this manner, prevent the two halves of the ceiling plate from being moved laterally of each other when held in locked position.

20 To apply the floor and ceiling plate to a pipe or other device, the locking tongue 21 is disengaged from the locking lug 23, and the two halves of the ceiling plate are swung apart and clasped upon the pipe at a place adjacent the ceiling, wall or floor, wherever it is desired to place the ceiling plate. After the ends of the two halves have been brought together into a locked condition, the ceiling 25 plate is bodily moved into contact with the surface of the ceiling, wall or floor, as the case may be.

It will be observed that the resilient fingers 17 are bent down somewhat when the ceiling 30 plate is applied to the pipe, and that all of the fingers grip the pipe between them and prevent the ceiling plate from being moved away from the surface of the ceiling, wall or floor. Should occasion require the removal of 35 the ceiling plate, a sharp or pointed instrument is inserted through the aperture 24 and the locking tongue pressed back out of engagement with the locking lug, whereupon the two halves of the ceiling plate may be readily unclasped from the pipe or other device and removed therefrom.

More or less variation of the exact details of construction is possible without departing from the spirit of this invention. I desire, 40 therefore, not to limit myself to the exact form of the construction shown and described, but intend, in the following claims, to point out all of the invention disclosed herein.

I claim:

50 1. The combination with an annular body portion formed with plate holding lugs at its inner and outer margins, of a spring plate secured on the rear side of said body portion by said lugs and formed with resilient radially extending fingers, the free ends of which are disposed in a circular line.

55 2. The combination of a body portion composed of two companion halves and means for securing said halves together, of two arcuate spring plates secured upon the rear

side of said body portion and formed with resilient fingers, the free ends of which are disposed in a circular line.

3. The combination of a body portion composed of two companion halves pivotally connected together, and means for locking the free ends of said halves together, and two arcuate spring plates secured to the rear side of said body portion and formed with radially extending resilient fingers, the free ends of which are disposed in a circular line.

4. The combination of a body portion composed of two companion halves pivotally connected together and locking means for securing said halves together, said body portion being formed with plate gripping lugs at its inner and outer margins, and two arcuate spring plates secured upon the rear side of said body portions by said lugs and formed with radially extending resilient fingers, the free ends of which are disposed in a circular line.

5. The combination of an annular body portion formed with a rim along its outer edge and with a bead at its inner edge, there being plate gripping lugs formed upon the edges of said rim and bead, of an arcuate spring plate contacting with the rear face of said body portion and having bent up tongues entering said beaded part of the body portion, said spring plate being secured on the body portion by said gripping lugs and having radially extending resilient fingers intermediate said tongues, the free ends of which fingers are disposed in a circular line.

6. The combination with an annular body portion adapted to surround a pipe and being formed with bent up plate holding lugs at its inner and outer margins, of an arcuate spring plate formed with resilient fingers at its inner margin, the free ends of which fingers are disposed in a circular line, said plate being secured on the rear side of the body portion by said lugs.

7. The combination with an annular body portion composed of two companion halves pivotally connected together, of two arcuate spring plates, secured to the rear side of each half of the body portion and formed with resilient fingers at its inner margin, the free ends of which are disposed in a circular line, one of said spring plates being formed with a slotted locking tongue adapted to overlap the part of the body portion containing the other spring plate, and said last mentioned part of the body portion containing a locking lug adapted to enter the slot of said locking tongue.

8. The combination with an annular body portion composed of two companion semi-circular halves pivotally connected together, of two arcuate spring plates secured to the rear of each half of the body portion and formed with resilient fingers, the free ends of

which are disposed in a circular line, there being a slotted locking tongue on one of said halves, and a co-operating locking lug on the other half adapted to enter the slot in the tongue to lock the two halves together, and there being lugs on the meeting edges of said halves, one lug on the rear side of each half and adapted to overlap an edge portion of the other half and acting to prevent lateral movement of the two halves relative to each other.

9. The combination of an annular body portion composed of two semi-circular halves pivotally connected together, of two arcuate spring plates, secured to the rear of each half of the body portion and formed with resilient pipe gripping fingers, one of said halves of the body portion being formed with a locking lug and the spring plate on the other half being formed with a slotted locking tongue co-acting with the lug to lock the two halves of the body portion together, and there being an aperture in one of the halves located behind said locking tongue, whereby access may be had to the locking tongue for disengaging it from the locking lug.

10. As a new article of manufacture, a two part floor and ceiling plate conformed to surround a circular body, there being pivotal and latch connections between the two parts whereby they may be opened out or closed together, a spring plate associated with each floor and ceiling plate part having radially extending resilient fingers adapted to engage yieldingly with the circular body, and retaining means provided on each plate part for engaging with opposite edges of the spring plates whereby to hold the same in assembled relation with the flange.
